SLUG CASTING MACHINE

Harold A. Burt, St. Albans, N. Y., assignor to
Mergenthaler Linotype Company, a corpora-
tion of New York

Application February 5, 1934, Serial No. 709,754

27 Claims. (Cl. 199—47)

This invention relates to slug casting machines, such as linotype machines of the general organization represented in United States Letters Patent No. 436,532 to O. Mergenthaler, wherein circulating matrices are released from a magazine in the order in which their characters are to appear in print, and then composed in line, the composed line transferred to the face of a mold, the mold filled with molten metal to form a slug or linotype against the matrices which produce the type characters thereon, and the matrices thereafter returned through distributing mechanism to the magazine from which they started. More particularly, the invention is directed to certain improvements which adapt these machines, when so desired, automatically to cast a predetermined plurality of duplicate type slugs and of blank slugs, such improvements being herein presented in the nature of an attachment which can be applied substantially to all commercial machines with practically little or no alteration.

As is well known in these machines, the means for presenting the composed line to the mold includes a transporter or so-called first elevator which first descends to position the line between the pair of clamping jaws for justification, and after the casting operation ascends to permit transfer of the line to the second elevator from which the matrices pass to the distributing mechanism. Also, as is well known, one of the clamping jaws is fixed (except for a limited movement to operate the customary pump stop), and the other (usually the left-hand jaw) adjustable to different positions to accord with the length of the mold slot or the length of the composed line in its justified condition, the position of such adjustable jaw being determined by an adjustable banking stop which however does not interfere with the free movement of the jaw up against the relatively fixed jaw in the absence of a matrix line between them.

In carrying out the present invention in its preferred embodiment (although the invention is not limited to such embodiment as will later appear), a mechanism is provided operating automatically during predetermined cycles of operation of the machine to arrest the transporter in a position preventing transfer of the line therefrom so that the line is presented a plurality of times to the mold to cast a corresponding plurality of duplicate type slugs, and other mechanism provided likewise operating automatically during other predetermined cycles of operation of the machine for moving the left-hand jaw into contact with the right-hand jaw to close the mold completely

at one side, so that blank slugs may be cast in the mold against the smooth side face of the left-hand jaw during such cycles, the operation of the machine throughout the casting of type slugs and blank slugs being rendered continuous by suitable automatic mechanism provided for the purpose.

The invention also contemplates the provision of means for preventing the delivery of a second composed line to the transporter during the automatic casting of the duplicate type slugs and blank slugs, and a galley associated with the casting mechanism formed with a plurality of compartments for holding the slugs delivered from the casting mechanism in separate columns, the galley also having mechanism associated therewith for automatically delivering a type slug and a blank slug alternately into each of the compartments.

Among other uses, the invention is of special utility in the production of blank slugs for use in supporting the overhanging printing faces of L-shaped or T-shaped printing slugs (especially in the case of "low" slugs), such as are frequently employed in advertising and telephone book work, particularly where it is desired to cast a plurality of duplicate type slugs from each composed line, it being intended that the duplicate type slugs will be stacked in separate columns, and blank or filler slugs inserted alongside the bodies of the printing slugs and beneath the overhanging printing faces to support the latter.

The invention will be described in detail in the specification to follow, and the novel features will be set forth in the appended claims.

In the accompanying drawings:

Fig. 1 is a front elevation of a portion of a linotype machine, showing applied thereto the attachments for casting duplicate type slugs and blank slugs in accordance with the present invention;

Fig. 2 is a plan view of a portion of the machine illustrated in Fig. 1, showing the mechanism for rendering the machine continuously active throughout a plurality of cycles of operation, the mechanism for actuating the first elevator arresting stop into and out of active position, and the actuating mechanism for the mold closing means;

Fig. 3 is an enlarged plan view of a portion of the mechanism illustrated in Fig. 2;

Figs. 4, 5, 6 and 7 are plan views of the mechanism for actuating the first elevator arresting stop into and out of active position, and the means for actuating the gate which controls the delivery of slugs to the different compartments of the gal-

ley, the various figures showing the mechanism at different phases of operation;

Figs. 8 and 9 are sectional views on lines 8—8 and 9—9 of Figs. 6 and 7, respectively;

5 Fig. 10 is a sectional view through a portion of the actuating mechanism for the first elevator arresting stop and the gate controlling the delivery of slugs to different compartments of the galley;

10 Fig. 11 is an elevational view partly in section of a portion of the apparatus for actuating the first elevator arresting stop, and the means controlling the delivery of slugs to the galley;

15 Fig. 12 is a view in perspective of the apparatus shown in Fig. 11;

Fig. 13 is a perspective view of a portion of the machine, showing the stacking (in the galley) of the type slugs with overhanging face portions and blank slugs which support such overhanging face 20 portions.

25 In the operation of the commercial linotype machine in the customary manner for the production of printing slugs, the matrices as they are released from their storage magazine are delivered to and composed in line in an assembler A, which is then manually elevated to raise the composed line to a delivery slide B which thereupon transfers the line to the line transporter or first elevator C. Upon receiving the line, the first elevator 30 descends to position the line between the left-hand clamping jaw v and the right-hand clamping jaw v¹ (both mounted on and carried by the vise frame V) in front of the then horizontally positioned slotted mold d on the rotatable mold 35 wheel D (the latter having previously been given a one-quarter rotation to carry the mold in use from the ejecting to the casting position). The line is then justified, and the mold wheel advanced from the rear to press the mold into contact with the matrix line and the two clamping jaws for the slug casting operation. After the 40 slug has been cast, the mold wheel D is given a three-quarter rotation to carry the mold d from its horizontal casting position back to its vertical 45 ejecting position (the latter being the normal position of rest of the mold), the slug ejected, trimmed and delivered to the galley R; the first elevator C in the meantime being raised to deliver the composed line to the matrix distributing 50 devices and finally coming to rest in its original or line receiving position.

55 As is well understood in the art, the various parts referred to, with the exception of the assembler A which is under manual control, are operated from the main drive shaft M of the machine which is caused to make one complete rotation for each cycle of operation. The shaft M is driven by an electric motor through the usual 60 spring actuated clutch (Fig. 2) which is thrown into action by a trip dog J carried by a cam J¹ fast to the main shaft. When the parts are at rest, the dog J engages and depresses a stop lever J² which, when so depressed, acts through the usual connections to disengage the clutch. When 65 however, the dog J is moved laterally to clear the stop lever J², as is done when the lever arm C² swings to the left upon the release of the delivery slide, the clutch actuating spring is allowed to engage the clutch and thus start the operation of 70 the machine.

75 The trip dog J is also under manual control, there being employed for this purpose a train of connections leading to a control lever j at the front of the machine, and which comprises in part a vertical sleeve J³ mounted to turn upon a fixed

rod J⁴, and which is provided near its upper end with a radially extending arm J⁵ arranged in position to engage the trip dog. This train of connections also includes a radially extending arm J⁶ provided near the lower end of the sleeve J³, and which extends into the path of an upwardly extending pin J⁷ located on a rod J⁸, leading to the front of the machine, where it is connected to the control lever j by a toggle joint consisting of a link j¹ and a rearwardly extending arm j² of the 10 control lever j. By this arrangement, when the control lever j is swung forwardly, the sleeve J³ is manually rotated, and the arm J⁵ caused to move the trip dog J clear of the stop lever J², so that the clutch may be engaged in the manner 15 above stated. The details of the clutch control mechanism are fully shown and described in the Rogers Patent No. 661,386, and being so well known, they do not require any further description 20 here.

25 To complete the identification of the well known parts which function in the operation of the instant invention, it may be added that the main shaft M is also provided with a plurality of cams which rotate once during each machine cycle 30 of operation, any one of which may be employed to control the device herein described for rendering the machine continuously operative for a plurality of cycles of operation. In the embodiment 35 shown, the control is effected from the drive gear M¹ (Fig. 2), but as stated before, it is not essential that this particular element be used, since any periodically rotating element on the main shaft may be used for the purpose.

40 The parts so far described and their normal mode of operation in casting single slugs, in themselves constitute no part of the present invention, and are or may be of any suitable construction, such for instance as discussed in the previously 45 mentioned Letters Patent No. 436,532, or as presented in the commercial linotype machine.

45 As already stated, the improved equipment is intended to adapt the machine automatically to cast a plurality of duplicate type slugs from each of the composed lines and thereafter a plurality of blank slugs or fillers, the machine being maintained in continuous operation throughout the casting of both the type slugs and the blank slugs. To this end, there are employed means which may be called into action when desired for actuation 50 by a periodically moving element of the machine, and during predetermined cycles of operation to prevent the first elevator C from ascending to its uppermost position, thereby preventing the transfer of the composed line therefrom, and permitting the composed line to be returned to the casting 55 mechanism a plurality of times to cast a corresponding plurality of duplicate type slugs.

60 In other predetermined cycles of operation blank slugs are cast and for this purpose the left-hand clamping jaw v (which as usual banks against a manually adjustable stop on the vise frame and thus determines the length of the justified matrix line and is movable from said 65 adjusted position up against the right-hand jaw v¹ when no matrix line is present) is utilized as the means for closing the mold by thus moving the jaw, and such movement of the jaw is in the embodiment illustrated, effected by mechanism actuated 70 automatically by the movement of the mold wheel D, and in such manner that the jaw v will be moved to close the mold d. The particular mechanism illustrated for actuating the clamping jaw to close the mold forms the subject 75

matter of my Patent No. 1,955,621, dated April 17, 1934.

The mechanism necessary for the control of the elements involved in rendering the machine continuously active during the casting of the duplicate type slugs and blank slugs and for locking the assembler A to prevent delivery of a second line to the first elevator C during the casting of such slugs are actuated from a single slide member S 10 slidably mounted in a bracket S¹ fixed on the vise frame V and actuated through means including a settable control device F actuated from a periodically rotating element of the machine, as for instance the driving gear M, which device may be 15 set so as to cause the machine to pass through any predetermined number of cycles of operation without stopping. The mechanism for this purpose is similar to that disclosed in the Frolander Patent No. 1,971,399, dated August 28, 1934.

It may be stated here however that the invention is not limited to the particular form or embodiment herein disclosed, but may be carried out in connection with a mold supported in other ways, by the use of mold closing means other than 25 the clamping jaw, by the use of other arrangements for maintaining the machine continuously operative throughout a number of cycles of operation, and by using other mechanism for arresting the first elevator in a position to prevent 30 transfer of a line therefrom, the essence of the invention residing broadly in the provision of means actuated automatically for casting a predetermined number of duplicate type slugs and a predetermined number of duplicate blank slugs 35 while maintaining the machine in continuous operation.

As more fully described in the Frolander patent previously referred to, the slide S, when in its rightmost position, operates the elements necessary for arresting the first elevator C in a position preventing transfer of a line therefrom, for locking the assembler A to prevent the delivery of a second line to the first elevator and for rendering the clutch control dog J inoperative so that 45 the line may be again returned to the casting mechanism during subsequent machine cycles of operation for casting duplicate slugs; whereas the slide S, when in its leftmost position, renders such elements inactive, so that the line may be 50 transferred from the first elevator for distribution in the usual manner, and a new composed line delivered thereto.

According to the present invention, the slide S is employed for the same purposes, except that 55 the means for arresting the first elevator in a position to prevent line transfer is disengaged from the slide and operated from another control element, in order that the arresting device may be operated independently of the mechanism 60 which renders the machine continuously operative throughout the casting of the duplicate type and blank slugs.

The position of the slide S is determined by an 65 adjustable control member F arranged to provide a large variety of adjustments, whereby the number of cycles through which it is desired to operate the machine continuously may be varied as desired, the adjustable member F being such that the slide S on the vise frame is maintained 70 in its active or operative position for a predetermined number of machine cycles of operation as determined by the adjustment. The adjustable member F effects its control of the slide through a lever L pivoted substantially at its mid-point to 75 a bracket L¹ mounted on the machine frame, the

lever being connected at its front end (Figs. 2, 3, and 11) to the slide S by means of a retractable pin L² arranged at the end of the lever and projecting upwardly between the bifurcated arms S² of a member S³ secured to the slide. 5

The control member F (Fig. 2) is carried by a rear extension of the bracket L¹ and is provided with a plurality of cam members F¹ (twelve in the particular embodiment shown) carried by a plate F² and which may be adjusted into and 10 out of alignment with the rear end of the lever L. Underlying the plate F² is a ratchet wheel F³ adapted to be engaged by a stud M² carried by the drive gear M¹, the arrangement being such that upon each complete rotation of the drive 15 gear, the control member F will be rotated through a distance equal to the pitch between two cam members. When the control member is rotated to bring an aligned cam F¹ in operative 20 relation with the end of the lever L, said lever will be actuated in a counterclockwise direction 25 against the pull of a spring L³ anchored to the supporting bracket L¹ to actuate the slide S to the right, in which position, as hereinbefore stated, the control elements operated by the slide are rendered active to effect the continuous 30 operation of the machine.

If it is desired to maintain the machine in continuous operation throughout four complete cycles, as for instance when it is desired to cast 35 automatically two duplicate type slugs and two duplicate blank slugs, the cam elements F¹ are adjusted so that every fourth cam element is out of alignment with the lever and the three intervening cam elements in alignment therewith. 40 When the machine is in a position of rest, an unaligned cam F¹ will be opposite the end of the lever L, in which position the slide S is in its leftmost or inactive position. When the machine is started, as by raising the assembler elevator A to deliver a line to the first elevator C, the machine will pass through one cycle of operation during which the stud M² carried by the drive gear M will actuate the cam plate F² to bring the next cam opposite the end of the lever. As this 45 cam is in alignment with said lever, the lever is rotated and actuates the slide S to the right or active position, wherein the clutch control dog J is rendered inoperative to stop the machine. Another cycle of operation is thus inaugurated 50 and as the next two cams F¹ are adjusted into a position wherein they align with the end of the lever L, the machine will continue in operation for two more cycles (four in all), or until the next unaligned cam is brought opposite the end 55 of the lever, whereupon the latter under the influence of the spring L³ will actuate the slide S to the left, permitting the clutch control dog J again to become operative to stop the machine. The construction of the adjustable control member F is more fully described in the Frolander 60 patent previously referred to.

When the slide S is in its rightmost position, the clutch control dog J is rendered inoperative by a train of connections including the usual 65 manual devices provided for this purpose. Referring to Figs. 2 and 3, the usual bracket which carries the manual control lever j is replaced by a bracket J⁹, having a forward extension, adjacent the outer end of which is pivoted a plate 70 J¹⁰. When the slide S is moved to the right, this plate is swung in a counterclockwise direction to actuate the rod J⁸ forwardly through the medium of a tension spring J¹¹ attached to said rod. When this occurs, the sleeve J³ of the clutch con- 75

trol mechanism is rotated (as is usual when the machine is started by the manual lever j), and the arm J^5 caused to move the trip dog J clear of the stop lever J^2 , the clutch remaining engaged continuously as long as the slide S on the vise frame V remains in its rightmost position, or during a plurality of cycles of operation as determined by the setting of the control element F .

As shown in Fig. 3, the rotation of the plate J^{10} is effected from the slide S through a dog S^4 carried at the right end of the slide. This dog has a beveled end which contacts with a downwardly extending pin J^{12} on the plate J^{10} to swing the latter in a counterclockwise direction to render the clutch control dog J inoperative. When the slide S is returned to normal position, during the last of the group of continuous cycles, the plate J^{10} is likewise returned to normal position as determined by an upstanding pin J^{13} , 20 on the plate, abutting against the edge of the support bracket J^9 , this movement of the plate being caused by the tension of the spring J^{11} . It might be here stated that the slide S is releasably held in either of its adjusted positions 25 by a spring pressed ball detent S^5 held by a plug threaded into the bracket S^1 , and engaging into either one of a pair of recesses S^6 formed in the bottom of the slide for this purpose.

As stated before, it is desirable to prevent the 30 delivery of a second composed line to the first elevator C during the casting of the duplicate type and blank slugs. This is accomplished by locking the assembler A in normal position during those predetermined cycles when the machine 35 is operating continuously, means also being provided for releasing the assembler after the last cycle, to permit a new line to be delivered to the elevator. For this purpose there is provided a dog K adapted to be swung into and out of 40 vertical alignment with a projecting lug A^1 on the assembler A . Thus, when the dog K is brought into active position overlying the lug A^1 , which operation is brought about by the movement of the slide S on the vise frame to the right, 45 upward movement of the assembler is prevented; whereas, when the dog K is moved to inactive position out of alignment with said lug, the assembler may be operated in the usual manner to deliver a line which has been composed therein 50 to the first elevator.

As shown in Fig. 1, the dog K is mounted on the upper end of a rod K^1 carried by a bracket J^{14} , formed as an integral part of the bracket J^9 carrying the manual control lever j . At its lower end the rod K^1 has a radially extending arm K^2 carrying an adjustable screw K^3 at its outer end, adapted to abut against the edge of the rearwardly extending arm j^2 of the manual control lever j . When the rod J^8 is pulled forwardly by the operation 60 of the slide S on the vise frame to accomplish the setting of the elements for rendering the operation of the machine continuous, the manual lever j , through its link connection j^1 with the rod J^8 is likewise caused to swing forwardly, the arm j^2 of the lever j engaging the arm K^2 to swing the dog K into active position in alignment with the lug A^1 on the assembler A . The dog K will remain in active position as long as the slide S remains in its rightmost position, and thus will prevent the operator from sending a new line to the first elevator during the casting of the duplicate type slugs and the blank slugs. When the slide S is again moved to the leftmost position, 70 during the last cycle of the group, the rod J^8

is actuated rearwardly in the usual manner by the clutch dog controlling mechanism, to return the manual control lever j to normal position. The operation of the control lever in this manner permits the dog K to be moved out of alignment 5 with the lug A^1 on the assembler by a spring K^4 pulling on the arm K^2 and anchored to the bracket J^9 . If, for any reason, the spring K^4 does not withdraw the dog to inactive position, such action is positively effected by means of an 10 upstanding arm K^5 connected at the front end of the spaceband lever rock shaft, this arm having a spring-retained dog K^6 at its upper end adapted to coact with a pin K^7 extending radially from the vertical shaft K^1 which carries the assembler 15 lock dog K . With this arrangement, when the spaceband lever is swung to the left during the operation of the transfer slide after the casting of the last slug of the group, the spring-retained dog K^6 will contact with the pin K^7 , and positively 20 push the assembler lock dog K out of vertical alignment with the lug A^1 on the assembler. In the event of an interference preventing the release of the assembler lock dog, the dog K^6 will yield against the tension of its retaining spring, thus preventing breakage or other 25 harmful results to the various parts.

In describing the arrangement for maintaining the machine in continuous operation throughout a plurality of cycles, a condition has been selected wherein the machine is operated continuously for four cycles without interruption. In conformity therewith, there has been selected, by way of illustration, a condition of operation wherein two duplicate type slugs and two duplicate blank slugs are cast from the same mold during the four cycles of operation referred to. These cycles are inaugurated when the operator raises the assembler A wherein a line has been composed to permit the line to be transferred to 30 the first elevator C which thereupon descends to present the line to the mold to cast a type slug. The transporter C thereafter ascends in the usual manner, but at this phase of the cycle means are rendered active to arrest the transporter in a 35 position wherein the transfer of the line is prevented so as to permit the transporter again to present the line to the mold to cast a duplicate slug from said line. During the second cycle of operation (wherein the second duplicate slug is 40 cast), the first elevator arresting means are rendered inactive, permitting the elevator to ascend to its normal uppermost position for the transfer of the line. During the third and fourth cycles of operation, the mold d is automatically 45 closed by the left-hand jaw v , so that two blank slugs are cast during these cycles.

The means for limiting the upward movement of the first elevator C includes a stop N carried by a sleeve N^1 pivoted to a cross-bar V^1 of the 50 vise frame, and rotatable into active position wherein it aligns with a projecting lug c located near the lower end of the first elevator C . When the stop N is in active position, the first elevator will be arrested before reaching its uppermost 55 position by the banking of the lug c against the stop N , thus preventing transfer of the line therefrom. The transfer of the line is prevented by means of a pin c^1 carried by an arm c^2 mounted on the left end of the line supporting member C^1 , 60 the pin in the arrested position of the first elevator, resting in front of a projecting lug e on the end of the transfer slide E , which, of course, prevents the usual movement of the transfer slide to the right to effect transfer of the line. When 65

the stop N is rotated to its inactive position (wherein it is out of alignment with the lug c), the first elevator will ascend to its normal line transfer position, wherein the pin c¹ comes to rest above the level of the projecting lug e, thus permitting the operation of the slide E in the usual manner to transfer the line.

When it is desired to use the machine simply to recast duplicate slugs and not blank slugs, the stop N may be actuated from the slide S on the vise frame, as in the Frolander patent previously referred to, the means for connecting the stop to the slide including a bracket S⁷ secured at the left of the slide, and having a downwardly extending leg with a lower horizontal portion carrying an upstanding pin S⁸ which engages in a notch N² provided at the upper end of a crank arm N³ arranged to actuate the sleeve N¹ carrying the transporter arresting stop N. When the slide S is in its leftmost position, the stop N is out of alignment with the lug c on the transporter, whereas when the slide is moved to the right (in which position the machine is rendered continuously operative), the stop is actuated into alignment with the lug and will remain active so long as the slide is in its rightmost position, so that the number of duplicate slugs cast will correspond to the number of cycles during which the machine is in continuous operation.

When it is desired to use the machine to cast two duplicate type slugs and two duplicate blank slugs, the transporter arresting stop N is disconnected from the slide S, and other mechanism brought into action for actuating the transporter arresting stop N, so that the stop may be rendered active during the first cycle of operation of a group to arrest the transporter C in a position to prevent transfer of the line therefrom and inactive during the second cycle of operation to permit transfer of the line so that blank slugs may be cast in succeeding cycles of operation. Such mechanism is actuated from a periodically operated element of the machine (in the embodiment illustrated the right-hand justification rod O) and is independent of the slide S which, as previously stated, acts to maintain the machine in continuous operation throughout the casting of the type and blank slugs.

The stop N is disconnected from the slide S, by raising the actuating crank arm N³ so that the notch N² clears the pin S⁸ on the bracket S⁷, the connection of the crank N³ with the stop N for this purpose including a collar N⁴ formed at the lower end of the crank and encircling the sleeve N¹ which carries the stop, and a pin n threaded through the collar and projecting into a vertical slot n¹ formed in the sleeve, the arrangement being such that the crank N³ may be moved vertically but not rotatably with respect to said sleeve (see Figs. 8 and 9).

The crank N³ is lowered and raised into and out of active position by a member P having bifurcated extensions p, straddling the sleeve, and provided at their ends with pins p¹ extending radially inwardly and engaging in horizontal slots n² cut in the collar N⁴, the slots n² being of sufficient length to accommodate the active stroke of the crank N³ and the arresting stop N.

The mechanism for operating the first elevator arresting stop N when blank slugs as well as duplicate type slugs are desired, includes in part, a cam P¹ for actuating the stop into engagement, a cam P² for actuating the stop out of engagement, and a sprocket P³ which together with a circular filler plate P⁴ for positioning the member P and a

cam P⁵ for operating the mechanism for distributing slugs to the galley are ganged together (see Fig. 10) and rotatably mounted on a vertical shaft P⁶ to which they are secured by a friction plate P⁷ screwed to the shaft at its upper end. The shaft P⁶ is carried by a bracket P⁸, formed with a vertical portion secured to a lug V² on the vise frame, and having upper and lower horizontal extensions p², p³ through which the shaft P⁶ extends. The shaft P⁶ has two positions of adjustment, as determined by a handle P⁹ pinned to the shaft at its lower end, said handle being provided in its upper face with upstanding projections p⁴ arranged to extend into corresponding recesses p⁵ in the lower face of a downwardly projecting shank P¹⁰ on the bracket P⁸; the upper position of the shaft being one wherein the adjacent faces of the handle P⁹ and shank P¹⁰ are in contact, and the lower position one wherein the shaft has been refracted downwardly and given a quarter turn to bring the upper faces of the projections p⁴ in contact with the lower face of the shank. The shaft is held in each of its adjusted positions by the tension of a coil spring P¹¹ encircling the shaft and engaging between an abutment on the shaft and the upper face of the lower bracket portion P³.

When the shaft P⁶ is in its lower adjusted position (see Fig. 9), the cams P¹ and P² and the sprocket gear P³ are inactive; the crank N³ however being in position (as determined by the member P) to be operated from the slide S on the vise frame as previously described. When it is desired to cast duplicate type slugs and blank slugs, the shaft P⁶ is adjusted to its upper position causing the member P to effect the disengagement of the crank N³ from the slide S; bringing the cam P¹ into horizontal alignment with a cam plate N⁶ formed on the sleeve of the arresting stop N and which together cooperate to actuate said stop into active position wherein it aligns vertically with the lug c on the first elevator; bringing the cam P² into alignment with an interponent P⁶ pivoted on a stud P⁷ mounted on the bracket P⁸, and which in turn is in alignment with a projecting lug N⁶ formed on the sleeve of the arresting stop N, and which upon operation adjusts said stop to inactive position; and bringing the sprocket P³ into alignment with a pair of spring pressed pawls p⁸, p⁹, the pawl p⁸ being pivotally mounted at the end of a periodically operated lever P¹² which, upon each stroke, advances the sprocket in a clockwise direction through a distance of one tooth, and the pawl p⁹ pivotally mounted on a stud p¹⁰ threaded into the bracket P⁸, and pressed against the sprocket by a coil spring p¹¹ anchored at its ends in the pawl and the bracket, respectively, said pawl p⁹ serving to prevent retrograde movement of the sprocket.

The sprocket actuating lever P¹² is pivotally connected at its rear end to a rearward extension P¹³ of the bracket P⁸ and in the instant embodiment of the invention is operated from the right-hand justification rod O (Fig. 3); the connections for this purpose including a horizontal push rod O¹ (the one which operates the galley stacker) slidably mounted in a vise frame upright V³, and having a recess O² cut in the rod to accommodate the lever P¹², a pin and slot connection O³ for obtaining the pivotal movement of the lever from the linear movement of the push rod, and a roller O⁴ carried by the justification rod and which cooperates with a cam surface O⁵ formed at the left end of the push rod, the arrangement being such that for each downward stroke of the justification rod

O, the push rod O¹ is moved to the right, thus imparting sufficient movement to the lever P¹² to actuate the sprocket P³ through a distance of one tooth. A spring (not shown) is provided for returning the push rod to normal position.

Since, as is well known, the right-hand justification rod O is depressed three times during each cycle of operation of the machine, and as there are twelve teeth in the sprocket P³, the latter as well as the cam elements arranged to rotate integrally therewith, will be actuated through one complete rotation for every four complete cycles of operation of the machine.

The cam P¹ which actuates the first elevator arresting stop N into active position is provided with two diametrically opposed high portions p¹² arranged to engage the cam segment N⁵ on the stop, and with two intermediate low portions p¹³ which clear the segment. The cam P² which operates with the interponent p⁶ for actuating the stop N out of active position is likewise provided with two high portions p¹⁴ and intermediate low portions p¹⁵, the high portions of the cams P¹ and P² being spaced angularly with respect to each other in order that the stop be rendered active and inactive at the proper time intervals.

In Fig. 5, the cams are shown in normal position just at the conclusion of a group of cycles of operation or after the casting of the last blank slug, the lever P¹² being shown in solid lines just prior to its return to normal position (as shown in dot and dash lines).

The operator starts the machine by sending in a line to the first elevator and upon the first downward stroke of the right-hand justification rod O the sprocket P³ is moved through a distance of one tooth (see Fig. 6), moving the high portion p¹⁴ of cam P² just clear of the interponent p⁶, and the cam P¹ in a position to commence moving the arresting stop N into active position. Upon the next two downward strokes of the justification rod (both of which are completed before the first elevator starts to ascend to its line transfer position), the sprocket P³ is actuated through a distance of two more teeth, with the result that the high portion p¹² of the cam P¹ engages the edge of the cam segment N⁵ on the arresting stop, actuating the latter into active position wherein the stop aligns with the lug c arranged at the lower end of the first elevator C, the cam P¹ being brought to rest with its outer peripheral curved surface adjacent the correspondingly curved surface formed in the edge of the cam segment N⁵. In this way the stop is locked in its active position wherein it arrests the first elevator in advance of the line transfer position, so that the line may again be presented to the mold during the second casting cycle. Fig. 7 shows the positions of the cams after the second downward stroke of the right-hand justification rod.

As previously described, the machine is maintained in continuous operation throughout four cycles of operation, during the second of which a duplicate type slug is cast from the line which is returned to the mold. During this second cycle of operations, the sprocket P³ is again actuated through a distance of three teeth (before the first elevator starts upon its upward stroke) by the lever P¹², the first two strokes of the lever actuating the cam P¹ to a position wherein it clears the cam segment N⁵ on the stop (see Fig. 4) and the cam P² into a position wherein a high portion p¹⁴ is ready to engage the interponent p⁶. Upon

the third stroke of the lever P¹², the cam P² engages the interponent p⁶ which in turn engages the projection N⁶ on the sleeve of the arresting stop N, to swing the latter out of active position, or in other words, out of vertical alignment with the lug c on the first elevator C. During the second cycle of operation, therefore, full ascent of the first elevator is permitted, the line transferred in the usual manner, leaving the machine ready for the casting of the blank slugs which occurs 10 automatically during the next two cycles of operation.

It might be here stated that as the cams P¹ and P² each have two high portions arranged diametrically opposite, the first elevator arresting stop N will be actuated into active position during the third cycle of operation and out of active position during the fourth cycle of operation, but as blank slugs are cast during these cycles it makes no difference whether or not the first elevator is arrested before it reaches the line transfer position. The purpose of the cam design is merely to insure the proper relation between the cams and the elements operated thereby, since, due to the arrangement of the lugs p⁴ on the handle P⁹ of the shaft, the cams may be raised into active position at intervals of 180°. Although the shaft P⁶ is prevented from turning when the sprocket P³ is actuated, by the lugs p⁴ on the handle engaging in the recesses p⁵, sufficient friction is introduced by the plate P⁷ bearing against the cam P¹ to prevent relative rotation between the shaft and the gang of elements mounted thereon when the shaft is turned by hand. With this arrangement, the operator is assured that the cams will be in position to cause the arresting stop to operate in proper sequence whenever the cams and sprocket are adjusted to operative position.

As previously stated, during the last two cycles of operation, mechanism is rendered automatically operative to close the mold d so that blank slugs may be cast. The mechanism for this purpose is shown in Fig. 1 and is described more in detail in my Patent No. 1,955,621 previously referred to. As shown in Fig. 1, there is rotatably mounted on the vise frame V by means of a horizontal stud t carried by a bracket t¹ screwed or otherwise secured to the vise frame, a Geneva stop motion device consisting of a Geneva disc T or plate journalled on the stud t. The disc T is formed at four equi-distant points in its peripheral edge with radial slots t²; and fixed to the forward face of this disc is a cam plate T² which is formed with a high portion for 180° and with a low portion for the remaining 180°. This cam, in the rotation of the disc T in the manner presently to be described, is adapted to engage a roller T³ mounted (eccentrically for purposes of adjustment) on the lower arm of a vertically arranged jaw actuating lever T⁴ pivoted between its ends by a pin t³ to a horizontal arm projecting from the bracket t¹, the upper arm of the lever being pivoted to a horizontal link T⁵, which is in turn pivoted to the left-hand end of the left-hand clamping jaw v.

A spring T⁶, anchored at one end to the vise frame and connected at its opposite end to the lower arm of the jaw actuating lever, acts to retract or move the jaw to the left when the low portion of the cam T² is opposite the roller T³, such movement of the jaw in its extreme retracted position being limited by a stop screw t⁴ on the vise frame in position to be engaged by the lower arm of the jaw actuating lever T⁴.

The Geneva disc T is rotated by means by a pin d¹ removably fastened to the mold wheel D and projecting forwardly from the same near its peripheral edge, said pin in the successive rotations of the mold wheel entering and leaving the slots t² in the Geneva disc T in succession, and thereby imparting a quarter rotation to said Geneva disc at each complete rotation of the mold wheel D. In such rotary movements of the Geneva disc, the high portion of the cam T², by engaging the roller T³ on the lower arm of the jaw actuating lever T⁴, will shift the jaw v to the right until it contacts with the right-hand jaw v¹ and thus close the mold, so that molten metal injected into the mold slot by the usual metal pump, will form a blank slug therein. Actually, the range of action of the cam T² is sufficient to cause the left-hand jaw to move the right-hand jaw slightly to the right so as to operate the customary pump stop and permit the casting operation to take place.

The form of the cam T² shown in Fig. 1 will, in four successive rotations of the mold wheel, maintain the mold open for two cycles of operation of the machine and close the mold in the two succeeding cycles of operation of the machine. As a result, the machine will operate to cast blank slugs in the two cycles succeeding the casting of the two duplicate type slugs. Thus, starting with the parts in their position of rest, as shown in Fig. 1, the first cycle of operation of the machine will result in the casting of a printing slug, the cam T² being inactive before casting. As the mold after casting is carried from its horizontal casting position to its vertical ejecting position, the pin d¹ (located at the leading end of the mold) will operate the Geneva disc T and impart a quarter turn to the cam T², but as there will still be a low portion of the cam opposite the roller T³, the mold remains open during the second cycle of operation, thus permitting the casting of the second duplicate type slug in the manner previously described. However, as the mold after casting the second type slug is carried from its horizontal casting position to its vertical ejecting position, the Geneva disc T is again operated and another quarter turn imparted to the cam T², bringing the high portion thereof opposite the roller T³ and causing it to act upon the lever T⁴ to move the left-hand jaw v up against the right-hand jaw v¹ to close the mold for the next casting operation (the composed line which was positioned between the two jaws for the previous casting operations having of course been lifted out of the jaws before the left-hand jaw is moved over). The left-hand jaw remains in its mold closing position during the third casting operation and also during the fourth casting operation, since the quarter turn imparted to the Geneva disc after the third casting operation also brings a high portion of the cam T² opposite the end of the mold closing lever T⁴, and another blank slug will be cast during the fourth cycle. As the mold disc D is rotated to the slug ejecting position after the casting of the fourth slug (the second blank slug), the Geneva disc T is again rotated through a quarter turn, allowing the spring T⁶ to return the jaw to its original retracted position, wherein the jaws will be in position to receive a new line for the next series of castings. It will be noted that while the casting of a blank slug takes place in one cycle of operation of the machine, the left-hand jaw is automatically adjusted to its mold closing position in the machine cycle immediately

preceding, although subsequent to the slug casting operation which takes place in such preceding cycle. This allows ample time for the movements of the left-hand jaw to and from its mold closing position without interfering with the composed matrix lines as they are delivered to and later taken from casting position.

The various mechanisms just described provide for the automatic casting of two duplicate type slugs and two blank slugs while maintaining the machine in continuous operation throughout the various casting operations.

The two type slugs and two blank slugs which are cast during the four continuous cycles of operation of the machine are ejected from the mold in the usual manner and delivered to a galley R wherein they are stacked. In accordance with the invention, the galley is formed with two compartments for holding the slugs in separate columns, and the type slugs and blank slugs delivered alternately into each of said compartments.

The means for this purpose are in part similar to those disclosed in the Frolander patent previously referred to and include an inclined galley R provided with a pair of compartments R¹, R², a chute R³ for delivering the slugs ejected from the mold to the galley, and a vertically movable gate R⁴ arranged opposite the discharge end of the chute and between the two compartments of the galley, said gate being adapted when in its uppermost position to permit the slugs to be delivered for stacking in the lower compartment R², and when in its lowermost position to arrest the slugs for stacking in the upper compartment R¹, each compartment of the galley further being provided with the usual sliding plate R⁵ against which the slugs are stacked, and a stacker plate R⁶, formed on a single slug stacking lever R⁹ which serves for both compartments. The gate R⁴ is carried at the forward end of a fore-and-aft lever R⁷ pivoted at its rear end to a pair of spaced lugs R⁸ carried by the mounting for the slide S. Spaced somewhat forwardly from the pivot, the lever R⁷ is provided with an upstanding lug r upon which there is slidably mounted an adjustable plate r¹, slotted as at r², to accommodate screws threaded into the lug for retaining the plate r¹ in either of two adjusted positions. The plate r¹, at its lower end is provided with a portion r³ bent to the right and extending downwardly at a slight angle, said portion being adapted for engagement by an upstanding pin s carried by the slide S, the arrangement being such that when the slide is in its leftmost position (see Fig. 12), the pin clears the plate and permits the gate to rest in its lowermost position, whereas when the slide is actuated to the right, the pin s engages the portion r³ of the plate to lift the lever R⁷ and place the gate in its uppermost position.

In the present arrangement, however, where it is desired to deliver the slugs cast in a plurality of successive cycles of operation alternately into the different compartments of the galley, the plate r¹ is adjusted to its upper position wherein the lower portion r³ clears the pin s (such course being rendered necessary as the slide is maintained in its rightmost position throughout a plurality of successive cycles, and consequently would hold the gate in its uppermost position throughout such cycles) and other mechanism rendered active, actuated from a periodical operating element of the machine, for alter-

nately raising and lowering the gate R^4 during successive cycles of operation of the machine.

Such mechanism includes in part a lever W , pivoted between its ends on the vise frame V , and having its upper portion curving upwardly and engaging at its upper end beneath the lever R^7 carrying the gate R^4 , and having its lower portion extending downwardly to engage at the front end of a fore-and-aft lever W^1 pivoted at its center to the bracket P^8 . When the shaft P^6 carrying the arresting stop actuating cams P^1 , P^2 is in its raised or active position, the lever W^1 is in alignment with the cam P^5 constituting one of the elements ganged together on the shaft P^6 and which thus makes one complete rotation for every four cycles of operation of the machine. The cam P^5 has two diametrically opposed high portions with intervening low portions, each portion taking up one quarter of the periphery of the cam, and when the end of the lever W^1 engages a low portion of the cam P^5 , the gate R^4 rests in its lower position wherein slugs are delivered and stacked in the upper compartment R^1 of the galley, whereas when the end of the lever W^1 is engaged by a high portion of the cam P^5 , the lever W^1 is pivoted counterclockwise, rocking the lever W , and raising the lever R^7 to lift the gate R^4 to its upper position wherein the slugs are permitted to be delivered into the lower compartment R^2 of the galley. The weight of the gate lever R^7 and the unbalanced weight of the lever W are sufficient to maintain the end of the lever W^1 in contact with the periphery of the cam P^5 . As a high portion of the cam P^5 is active during alternate cycles of operation (say the first and third of a group of four) and a low portion active during different alternate cycles (say the second and fourth), it is apparent the slugs will be delivered alternately into different compartments of the galley; and where two duplicate type slugs are cast in the successive cycles of operation, such slugs will be delivered into different compartments of the galley and the same will be true of the blank slugs delivered in the next two successive cycles of operation.

The slug lever R^9 is of the usual type carried by an arm pivoted to the vise frame, and having a projection R^{10} extending rearwardly for engagement by the push member O^1 which is actuated from the right-hand justification rod, the construction of these levers and their actuating mechanism being so well known that no further description is needed here.

As mentioned at the outset, the invention has special utility when casting slugs with overhanging faces as for instance L-shaped or T-shaped slugs and the blank slugs usually employed for supporting said faces, since with the present invention the type slugs and blank slugs may be stacked automatically, thus obviating the manual labor of arranging the slugs by hand. In Fig. 13, there is shown, by way of illustration, slugs Z having body portions Z^1 and overhanging faces Z^2 , and blank slugs X without such faces, the height of the blank slugs being such that they may be arranged along side of the body portions Z^1 of the slugs Z and under the overhanging faces Z^2 thereof. As each type slug Z is delivered to the galley, it is automatically pushed by the stacker plate R^6 up against the slug previously delivered. The next slug to be delivered to the same compartment will be a blank slug X , which is pushed likewise by the stacker plate beneath the overhanging face Z^2 of the slug Z previously delivered. When a compartment

is filled, the slugs are ready for use without further arranging.

As before explained, in casting the blank slugs X , the left-hand clamping jaw v is moved toward the companion jaw to close the mold slot 5 at the front, no matrix line being presented to the mold during this particular cycle of operation. In casting the overhanging slugs Z , on the other hand, a composed matrix line is presented to the mold in the regular way and the matrices 10 are formed with deep routing notches which communicate with the mold slot and which form the overhanging type carrying portions of the slugs. This practice of casting overhanging slugs is well known and, for purposes of illustration, 15 reference may be had to the Reade Patent No. 1,218,803, dated March 13, 1917.

It will be apparent from the foregoing description that the device of the invention may be readily attached to the commercial linotype machine with little change, since all of the control mechanisms are arranged in compact units, it being necessary only to make the necessary drillings in the frame of the machine.

It will be further understood that the invention is not limited to the alternate casting of two type slugs and two blank slugs, since any desired number of each form of slug may be produced, merely by changing the form of the cams P^1 , P^2 actuating the first elevator arrest- 25 step N , the number of teeth in the sprocket P^3 , the form of the cam T^2 actuating the left-hand vise jaw v and the setting of the control device F for determining the number of cycles through which the machine is to operate continuously. Also, if desired, the control device F may be removed and another substituted, giving a greater number of settings, whereby the number of cycles obtainable in a group may be varied to a larger extent. 40

In the accompanying drawings the invention has been shown merely by way of example and in preferred form, and obviously many variations and modifications may be made therein which will still be comprised within its spirit. It is to 45 be understood, therefore, that the invention is not limited to any specific form or embodiment, except insofar as such limitations are specified in the appended claims.

Having thus described my invention, what I 50 claim is:

1. In a slug casting machine, the combination of means for casting a type slug and a blank slug in different cycles of operation of the machine, means normally acting to arrest the operation of the machine after the casting of each slug, and automatic means for rendering said arresting means inactive as required to maintain the machine continuously operative throughout the casting of said slugs. 60

2. In a slug casting machine, the combination of a mold, means for presenting a line to the mold to cast a type slug during one cycle of operation of the machine, means for closing the mold to cast a blank slug during another cycle of operation of the machine, means normally acting to arrest the operation of the machine after the casting of each slug, and automatic means to render said arresting means inactive as required for maintaining the machine in continuous operation throughout the casting of both slugs. 65

3. In a slug casting machine, the combination of means for casting a plurality of type slugs during given cycles of operation, means for casting a plurality of blank slugs during other cycles of 75

operation, means normally acting to arrest the operation of the machine after the casting of each slug, and automatic means for rendering said arresting means inactive as required to maintain the machine continuously operative throughout the casting of said slugs.

4. In a slug casting machine, the combination of means for casting a plurality of type slugs during given cycles of operation and a plurality of blank slugs during other cycles of operation, means normally acting to arrest the operation of the machine after the casting of each slug, and automatic means to render said arresting means inactive as required for maintaining the machine in continuous operation during the casting of both the type and blank slugs.

5. In a slug casting machine, the combination of a mold, means actuated automatically for presenting a composed line to the mold a plurality of times to cast a corresponding plurality of duplicate type slugs during given cycles of operation, means actuated automatically for closing the mold to cast a predetermined number of blank slugs during other cycles of operation, means normally acting to arrest the operation of the machine after the casting of each slug, and automatic means to render said arresting means inactive as required for maintaining the machine in continuous operation during the casting of both type and blank slugs.

6. In a slug casting machine, the combination of a mold, a transporter for presenting a composed line to the mold, means for transferring the composed line from the transporter after casting, means to prevent transfer of the line therefrom during given cycles of operation for the casting of duplicate type slugs, and means for closing the mold during other cycles of operation for the casting of blank slugs.

40 7. In a slug casting machine, the combination of a mold, a transporter for presenting a composed line to the mold, means for arresting the transporter in a position to prevent transfer of the line therefrom, means for closing the mold to cast blank slugs, means operating automatically for rendering the transporter arresting means active during given cycles of operation, means operating automatically for rendering the mold closing means active during other cycles of operation, whereby the line is presented to the mold a plurality of times to cast a corresponding plurality of duplicate type slugs and the mold closed to cast blank slugs, and settable means for rendering the machine continuously active throughout the casting of the type slugs and the blank slugs.

60 8. In a slug casting machine, the combination of a mold, means actuated automatically for presenting a composed line to the mold a plurality of times to cast a corresponding plurality of duplicate type slugs during given cycles of operation, means actuated automatically for closing the mold to cast a predetermined number of blank slugs during other cycles of operation, and a settable control device for maintaining the machine in continuous operation throughout the casting of the type and the blank slugs.

70 9. In a slug casting machine, the combination of a mold, a transporter for presenting a composed line to the mold, mechanism actuated from a periodically operated element of the machine for preventing transfer of the line from the transporter during predetermined cycles of operation whereby the line may be presented to the mold a plurality of times to cast a corresponding plurality of duplicate type slugs, means actuated

automatically for closing the mold to cast blank slugs during other predetermined cycles of operation of the machine, and settable mechanism for maintaining the machine in continuous operation throughout the casting of the type and the blank slugs.

10. In a slug casting machine, the combination of a mold, a transporter for presenting a composed line to the mold, means actuated from a periodically operated element of the machine for preventing transfer of the line from the transporter during given cycles of operation whereby the line may be presented to the mold a plurality of times to cast a plurality of duplicate type slugs, means actuated automatically during other given cycles of operation to close the mold to cast blank slugs, and independently operated control mechanism settable in accordance with the number of type slugs and blank slugs to be cast for maintaining the machine in continuous operation throughout the casting of said slugs.

15 11. In a slug casting machine, the combination of a mold, a transporter for presenting a composed line to the mold, a stop for arresting the transporter in a position to prevent transfer of the line therefrom, mechanism actuated from a periodically operated element of the machine for rendering said stop active during one cycle of operation and inactive during another cycle whereby a composed line is presented to the mold a plurality of times to cast a corresponding plurality of duplicate type slugs, means actuated automatically for closing the mold to cast blank slugs during still other cycles of operation of the machine, and settable mechanism for rendering the machine continuously operative throughout the casting of the type slugs and the blank slugs.

20 12. In a slug casting machine, the combination of a mold, a transporter for presenting a composed line to the mold, a stop for arresting the transporter in position to prevent transfer of the line therefrom, mechanism actuated from a periodically operated element of the machine and including cam elements for moving the stop into active position during predetermined cycles of operation whereby a line may be presented to the mold a plurality of times to cast a plurality of duplicate type slugs, and out of active position during other predetermined cycles of operation to permit transfer of the line, means for closing the mold during other predetermined cycles of operation to cast blank slugs, and mechanism settable in accordance with the number of type slugs and blank slugs to be cast for maintaining the machine in continuous operation throughout the casting of the type slugs and the blank slugs.

25 13. In a slug casting machine, the combination of means for casting a type slug and a blank slug in different cycles of operation of the machine, automatic means for rendering the machine continuously operative throughout the casting of said slugs, a galley, and means for stacking the type and blank slugs alternately therein.

30 14. In a slug casting machine, the combination of casting mechanism, a galley associated therewith and provided with a pair of compartments for holding the slugs delivered from the casting mechanism in separate columns, a movable gate associated with the galley and adapted, when in one position, to effect the delivery of slugs into one compartment and when in another position to effect the delivery of slugs into the other compartment, automatically actuated mechanism controlling the position of said gate, and independently actuated mechanism for render-

ing the machine continuously active throughout a predetermined plurality of casting cycles.

15. In a slug casting machine, the combination of a mold, a transporter for presenting a composed line to the mold, means actuated automatically for arresting the transporter in a position to prevent transfer of the line whereby the line may be presented a plurality of times to the mold to cast a corresponding plurality of duplicate type slugs in predetermined cycles of operation of the machine, means actuated automatically for closing the mold during other predetermined cycles to cast a plurality of blank slugs, a galley provided with a pair of compartments for holding slugs in separate columns, and means actuated automatically for delivering a type slug and a blank slug alternately into each of said compartments.

16. A combination in accordance with claim 15, wherein the transporter arresting device and the means controlling the delivery of slugs to the galley are operated from a common periodically actuated element of the machine.

17. A combination in accordance with claim 15, further characterized by the fact that means are provided acting independently of the means controlling the delivery of the slugs to the galley for maintaining the machine in continuous operation throughout the casting of the plurality of type slugs and the plurality of blank slugs therein referred to.

18. In a slug casting machine, the combination of a mold, a transporter for presenting a composed line to the mold to cast a type slug during one cycle of operation of the machine, means for casting a blank slug during another cycle of operation of the machine, automatic means for maintaining the machine in continuous operation throughout the casting of both slugs, and means for preventing the delivery of a second line to the transporter until after the blank slug is cast.

19. In a slug casting machine, the combination of a mold, a transporter for presenting a composed line to the mold to cast a type slug during one cycle of operation of the machine, means for casting a blank slug during another cycle of operation of the machine, automatic means for maintaining the machine in continuous operation throughout the casting of both slugs, a galley, means for stacking the type slugs and blank slugs alternately therein, and means for preventing the delivery of a second line to the transporter until after the casting of the blank slug.

20. In a slug casting machine, the combination of a mold, a transporter for presenting a composed line to the mold, an assembler wherein the line is composed, means for delivering the line from the assembler to the transporter, means actuated automatically for arresting the transporter in a position to prevent transfer of the line therefrom, whereby a line may be presented to the mold a plurality of times to cast a corresponding plurality of duplicate type slugs during given cycles of operation of the machine, means actuated automatically for closing the mold to cast blank slugs during other given cycles of operation, and means acting automatically to prevent delivery of a second composed line from the assembler to the transporter until after the casting of both the duplicate type slugs and the blank slugs.

21. In a slug casting machine, the combination of a mold, a transporter for presenting a composed line to the mold, means actuated automatically for arresting the transporter in a po-

sition to prevent transfer of the line therefrom, whereby a line may be presented to the mold a plurality of times to cast a corresponding plurality of duplicate type slugs during given cycles of operation of the machine, means actuated automatically for closing the mold to cast blank slugs during other given cycles of operation, and means acting automatically to prevent delivery of a second composed line to the transporter until after the casting of both the duplicate type slugs and the blank slugs. 5

22. In a slug casting machine, the combination of a mold, a transporter for presenting a composed line to the mold, an assembler wherein the line is composed, means for delivering the line from the assembler to the transporter, means actuated automatically for arresting the transporter in a position to prevent transfer of the line therefrom, whereby a line may be presented to the mold a plurality of times to cast a corresponding plurality of duplicate type slugs during given cycles of operation of the machine, means actuated automatically for closing the mold to cast blank slugs during other given cycles of operation, means for locking the assembler in a position to prevent the delivery of a line therefrom, means for normally stopping the machine at the conclusion of a cycle of operation, and settable mechanism for rendering the machine stopping means inactive and the assembler locking means active continuously throughout the casting of both the type slugs and the blank slugs. 20

23. In a slug casting machine, the combination of a mold, means for presenting composed lines to the mold to cast type slugs with overhanging faces, during given cycles of operation of the machine, means for casting blank slugs without overhanging faces during other cycles of operation of the machine, a galley, means for delivering the type slugs and blank slugs alternately 40 to the galley, and means for automatically stacking the blank slugs beneath the overhanging faces of the type slugs. 30

24. In a slug casting machine, the combination of casting mechanism for automatically casting a pair of duplicate type slugs and a pair of blank slugs in successive cycles of operation of the machine, a galley for receiving the slugs and provided with separate compartments, and means operating automatically to deliver a type slug and 50 a blank slug alternately into each compartment of the galley. 45

25. In a slug casting machine, the combination of casting mechanism for automatically casting a pair of type slugs and a pair of blank slugs, a galley for receiving the slugs and provided with a pair of separate compartments, a gate between said compartments, and means acting to operate said gate periodically, whereby a type slug and a blank slug are delivered alternately into each 60 compartment of the galley. 55

26. In a slug casting machine, the combination of a mold, means for presenting a composed line to the mold during given cycles of operation to cast type slugs with overhanging faces, means for closing the mold during other cycles of operation to cast blank slugs without overhanging faces, a galley for receiving the slugs, means controlling the delivery of slugs to the galley whereby the type slugs and the blank slugs are arranged alternately therein, and stacking mechanism associated with the galley for stacking the blank slugs alongside the type slugs and under the overhanging faces thereof. 70

27. In a slug casting machine, the combination 75

of a mold, a transporter for presenting a composed line to the mold, a stop for arresting the transporter in a position to prevent transfer of the line therefrom, mechanism actuated from a periodically operated element of the machine for moving the stop into active position during predetermined cycles of operation whereby a line may be presented to the mold a plurality of times to cast a corresponding plurality of duplicate type slugs and for moving the stop out of active position during other predetermined cycles of operation to permit transfer of the line, means actuated automatically during other predetermined cycles of operation for closing the mold to cast

blank slugs, a settable control device for maintaining the machine in continuous operation throughout the casting of the type slugs and the blank slugs, means also actuated by said settable control device for preventing delivery of a new line to the transporter throughout the casting of the type slugs and the blank slugs, a galley formed with two compartments for holding the slugs in separate columns, and means actuated from the mechanism controlling the transporter arresting stop for effecting the delivery of a type slug and a blank slug alternately into each compartment of the galley. 5 10

HAROLD A. BURT.
